UNITED STATES PATENT OFFICE.

CORNELIUS M. COUTTS, OF ISSAQAH, WASHINGTON.

SHELVING.

Application filed September 29, 1921. Serial No. 504,042.

To all whom it may concern:

Be it known that I, CORNELIUS M. COUTTS, a citizen of the United States, residing at Issaquah, in the county of King and State 5 of Washington, have invented certain new and useful Improvements in Shelving; and I do hereby declare the following to be a full, clear, and exact description of the invention, such as will enable others skilled 10 in the art to which it appertains to make and use the same.

This invention relates to new and useful improvements in shelving for supporting bolts of cloth and has for its primary object 15 the provision of a support having racks removable therefrom to permit the device to be used either as a center display or a wall display and also the removal of any of the racks from the support independent of the 20 other racks may be made to permit relative adjustment of the racks for accommodating large bolts of cloth when desired.

Another object of this invention is the provision of a shelving of the above stated 25 character, which will be simple, durable and efficient, and which may be manufactured and sold at a comparatively low cost.

With these and other objects in view as will become more apparent as the description 30 proceeds, the invention consists in certain novel features of construction, combination and arrangement of parts as will be herein-after more fully described and claimed.

For a complete understanding of my invention, reference is to be had to the following description and accompanying drawings, in which:—

Figure 1 is a plan view illustrating the racks arranged for center display,

40 Figure 2 is a view illustrating the racks arranged for wall display,

Figure 3 is a perspective view illustrating the support,

45 Figure 4 is a detail view illustrating a bracket for the support,

Figure 5 is a detail sectional view illustrating the means of attaching a rack to the support.

Referring in detail to the drawings, the 50 numeral 1 indicates a support constructed from channel iron providing bottom and side walls 2 and 3. The side walls 3 are provided with elongated openings 4 and slots 5. The slots 5 of one side wall are 55 in alinement with the elongated openings 4 in the other side wall for the purpose of

receiving resilient racks 6. The racks are identical in construction and reference to one specifically is thought sufficient for all and the rack includes a pair of resilient 60 strips 7 bent back upon themselves and one strip confined within the other. The free ends of the strips are secured together by the rivet 8 and said ends are reduced to form extensions 9 adapted to fit within the elongated opening 4 of the support while the strips adjacent to their free ends are provided with oppositely arranged notches 10 to receive projections 11 at the open end of the slot of the support so as to prevent 70 the strips from moving vertically out of the slot. To place or remove a rack from the support, the sides of the strips are compressed together disengaging the notches from the projections and the rack is then 75 lifted partly from the notch and pulled endwise to disengage the extensions from the opposite elongated opening. The rack is replaced on the support in a similar manner and as soon as pressure is released from the 80 sides of the strips, they spread apart and underlie the projections preventing the displacement of the rack from the support. The innermost strip of the rack is of a shorter length than the outermost strip and 85 is adapted to reinforce and strengthen the outermost strip. The racks when secured to the support contact normally with each other but are capable of flexing to receive and grip a bolt of cloth and support the 90 latter in a suspended position.

The racks being removable from the support will permit relative adjustment of the racks so as to accommodate bolts of cloth of extremely large size when desired by removing every other rack of the series of racks. The removal of the racks from the support also permit the device to be used for a center display with racks extending from each side of the support, or as a wall 100 display with the racks only extending from one side of the support.

A bracket 11 is provided with an attaching portion 12 provided with openings to receive suitable fasteners for securing the 105 same to a wall. The body portion 13 of the bracket is shaped to slidably receive one end of the support 1. The body of the bracket is of channel iron shape provided with inwardly directed flanges 14 to retain the 110 channel iron support within the body of the bracket.

While I have shown and described the preferred embodiment of my invention, it will be understood that minor changes in construction, combination, and arrangement of parts may be made without departing from the spirit and scope of the invention as claimed.

Having thus described my invention what I claim is:—

- 10 1. A shelving comprising a channel iron support having slots and elongated openings in its side walls and the slots of one wall disposed in alinement with the openings in the other wall, resilient racks projecting into the elongated openings and resting in the slots.
- 15 2. A shelving comprising a channel iron support having elongated openings and slots in its side walls and the slots of one wall disposed in alinement with the openings in the other wall, projections formed on the walls of the slots, resilient racks projecting into the elongated openings and resting in the slots under the projections.
- 20 3. A shelving comprising a channel iron support having slots and elongated openings

in its sides, the openings of one side alining with the slots of the other side, resilient racks constructed from strips of resilient material bent upon themselves and secured together and having their ends reduced to form extensions adapted to project into the elongated openings, said strips having notches alined with the walls of the slots, and projections formed on the walls of the slots and extending into the notches.

4. A shelving comprising a channel iron bracket, resilient racks extending from the support and detachably secured thereto, a bracket having a channel iron body portion receiving one end of the support, flanges formed on the channel iron portion of the bracket and overlying the channel iron support, said bracket having an attaching portion extending at right angles to the body portion.

In testimony whereof I affix my signature in presence of a witness.

CORNELIUS MAXWELL COUTTS.

Witness:

R. J. SCHNEIDER.
